CLAIM

The ornamental design for a wire strand attachment clip, as shown and described.

DESCRIPTION

This application is related to the following commonly owned co-pending patent application: U.S. patent application Ser. No. 17/406,911, entitled “Wire Strand Attachment Clip”.

FIG. 1 is a top perspective view of a wire strand attachment clip of our new design.

FIG. 2 is a bottom perspective view of the wire strand attachment clip of FIG. 1.

FIG. 3 is a bottom view of the wire strand attachment clip of FIG. 1.

FIG. 4 is a top view of the wire strand attachment clip of FIG. 1.

FIG. 5 is a left side view of the wire strand attachment clip of FIG. 1.

FIG. 6 is a right side view of the wire strand attachment clip of FIG. 1

FIG. 7 is a front view of the wire strand attachment clip of FIG. 1.

FIG. 8 is a rear view of the wire strand attachment clip of FIG. 1; and,

FIG. 9 is a cross-sectional view of the wire strand attachment clip of FIG. 1, taken substantially along line 9-9 of FIG. 8.
